UNITED STATES PATENT OFFICE.

RICHARD B. BUDIN, OF BROOKLYN, NEW YORK.

TOY.

1,424,982.

Specification of Letters Patent. Patented Aug. 8, 1922.

Application filed February 23, 1921. Serial No. 447,269.

To all whom it may concern:

Be it known that I, RICHARD B. BUDIN, a citizen of the United States, and a resident of the city of New York, borough of Brooklyn, county of Kings, and State of New York, have invented certain new and useful Improvements in a Toy, of which the following is a full, clear, and exact description.

10 Among the principal objects which the present invention has in view are: to provide an interesting toy adapted to startle and hold the attention; to provide a construction which is attractive, simple and 15 cheap.

Drawings.

Figure 1 is a vertical section of a toy constructed and arranged in accordance with the present invention.

20 Figure 2 is a side elevation thereof.

Figure 3 is a rear end elevation of the same.

Description.

25 As seen in the drawings a table 8 has dependent flanges 9 forming a continuous frame to enclose an elastic member 10 which is anchored at one end to a hook 11 and at the other with a bracket 12. The bracket 30 12 is rigidly attached to a thin metal platform 13 on which the image 14 of a dog or other animal or member is mounted, which in the operation of the apparatus is supposed to require a house such as indicated 35 by the numeral 15. The house 15 is permanently mounted on the table 8.

The platform 13 is wide enough to cover a slot 16 formed in the table 8. To assist in guiding the platform 13 when the same 40 is pulled forward by the elastic 10 there are provided pins 17 extended from the underside of the said platform.

The free end of a cord 18 is attached to the bracket 12. The cord 18 has a button 45 19 at the free end by means of which the cord is drawn backward and the image 14 is retracted through the doorway in the house 15. The image is held within the house 15 by means of a knot 21 which is 50 provided on the cord 18.

As seen best in Fig. 3 of the drawings the knot 21 is sufficiently small to pass freely

through a perforation 22 in the flange 9 at the rear of the image. Extending from the perforation 22 is a slot 23 which is made too 55 narrow to pass the knot 21, but sufficiently wide to receive the cord 18.

In the operation of the toy the button 19 is engaged and by means thereof the cord 18 is drawn back until the knot 21 passes 60 outside of the perforation 22, the elastic member 10 permitting the retractive movement of the bracket 12 and parts connected therewith in conformity with the movement of the cord 18. The cord 18 is then moved 65 sidewise into the slot 23 to be released until the knot 21 engages the sides of the slot 23. The image is then held in the alert position wherein the knot 21 is moved to align with the perforation 22. When so aligned 70 the elastic 10 is permitted to pull the bracket 12 in the image 14 from out of the house 15 to the position shown in Fig. 2 of the drawings. The sudden movement of the image 14 passing from the house 15 provides 75 a pleasing, startling sensation.

Where desired the toy may be provided with carrying wheels 24 and a pull cord 25 so that the toy may be drawn after the child or person entertained by or exhibiting the 80 toy. This also provides for the manufacture of the toy on a larger scale if it is found desirable.

Claim.

85 A toy as characterized comprising a table having an elongated narrow slot therein; a thin platform partially covering said slot and supported by said table, said platform having rigidly attached thereto, a perforated pendant bracket for extension through and below said slot; an open hook permanently disposed adjacent the forward end of said table in line with the perforation in said bracket; a perforated member 90 attached to said table at the opposite end thereof, the perforation in said member being aligned with the perforation in said bracket, said perforation having a contracted lateral extension; a non-elastic cord 95 operatively engaging said bracket and being extended through said perforation therein and through the perforation in the member at the rear of said table, said cord 100

equalling approximately the length of said table, and being provided with a knot adjacent said bracket, said knot being adapted for engagement by the contracted extension 5 of said perforation for restraining the platform and bracket connected therewith in a position adjacent the rear end of said plat-

form and an elastic member operatively uniting said hook and said bracket, said member being extended through the perforation in said bracket and adapted for extension over, for engagement by said hook. 10

RICHARD B. BUDIN.
